UNITED STATES PATENT OFFICE.

JAMES A. VARIAN, OF NORWALK, CONNECTICUT.

GARAGE.

1,102,828.

Specification of Letters Patent.

Patented July 7, 1914.

Application filed August 29, 1913. Serial No. 787,302.

To all whom it may concern:

Be it known that I, JAMES A. VARIAN, a citizen of the United States, and a resident of Norwalk, in the county of Fairfield and 5 State of Connecticut, have invented a new and Improved Garage, of which the following is a full, clear, and exact description.

This invention relates to garage structures, the idea being to provide a novel arrangement and construction of parts for installing or removing cars without collisions and the like and also for obviating the necessity of an extensive building construction which is now necessary due to the fact 10 that the floor spaces are left generally clear but weakened by reason of the bridging of the full width or area of the garage by floor beams, while the present invention permits a maximum amount of storage space and 15 weight to be supported within a predetermined area.

A further object of the invention consists in a novel arrangement for the floor of the garage wherein a turntable is provided 20 in novel relative position to an elevator and to a carrying floor for directing the cars or automobiles into the various stalls at either side or at one side of a central passage, or for directing the cars from the carrying 25 floor to the elevator for distributing the cars into the various stalls upon the upper floors of the building.

A further object of the invention is to provide in connection with the arrangement 30 specified, a wash stand also arranged in novel position to the turn table and carrying floor to permit the automobiles to be cleaned out of their stalls, thus insuring of better maintenance of the cars, while novel means 35 are provided for reinforcing the floor structure and for movably supporting the carrying floor which operates between the stalls for distributing the automobiles thereinto 40 without breakage or accidents.

With the above and other objects in view, 45 the invention resides more particularly in the peculiar combination and arrangement of parts which will be illustrated as a preferred embodiment in the drawings and described in the specification.

Reference is to be had to the accompanying drawings forming a part of this specification, in which similar characters of ref-

erence indicate corresponding parts in all the views, and in which—

Figure 1 is a plan view of the bottom floor of a garage with certain of the parts shown in section; Fig. 2 is a similar view of an upper or top floor plan of the garage; Fig. 3 is an enlarged vertical sectional view 55 through a fragmentary portion of a flooring and showing the manner of movably supporting the carrying floor which operates between the stalls of each floor of the garage; Fig. 4 is an enlarged cross sectional 60 view of one of the anti-friction bearings or rollers for supporting the carrying floor; and Fig. 5 is a detail perspective view of 65 one of the bracket bearings for supporting 70 said ball bearing rollers and permitting the replacement of the latter.

In the invention as illustrated in the drawings the garage is shown as embodying a housing or building, the walls of which are indicated by the numerals 10 and 11, 75 provided at spaced points with windows 12 and preferably provided with a bay window 13 having show windows 14 and a suitable private entrance 15 leading into the office space 16 having stairs or other form of passage 17 leading to the upper floors of the building. A show window 18 is also provided centrally at the front of the building behind which a barrier 19 is provided to produce an additional show space 20 having 80 connection with the space 16 by a door 21, while said space 16 also leads into the garage proper behind the barrier or partition 19 by means of a door 22. This arrangement may be considerably varied with 85 in the scope of the invention, which more particularly resides in the arrangement of stalls for storing the automobiles and means for affecting the disposition of such automobiles into the respective stalls without 90 collisions or accidents. For this purpose the front wall of the building is provided with a doorway 23 for the automobiles, which doorway may be closed by oppositely operating sliding doors 24 or otherwise. 95 Positioned immediately in rear of the door opening 23 is a turn table 25 which may be turned by any suitable source of power, such as a lever 26, so that as the cars enter through the door opening 23 and pass in to 100 the turn table they may be directed on to a 105

wash stand 27 to be cleaned or on to the carrying floor 28 to be distributed into a suitable stall forming a storing space in the garage. The floorings of the building are indicated by the numeral 29 and are preferably of reinforced concrete, reinforced at spaced points by vertical posts or pillars 30 disposed at such spaced relation, preferably about thirteen feet, to accommodate two automobiles in each stall 31 thus provided. These stalls are located at either side of a passageway 32 extending longitudinally of the building in rear of the barrier or partition 19, in each of which a carrying floor 28 is movable.

The wash stand 27 has its walls sloping toward a central drain 33, and after the cars are cleaned they may be directed on to the turntable 25 and then on to the carrying floor 28 or directly on to the carrying floor 28 and then distributed into any of the stalls upon the bottom floor. If, however, it should be desired to store the automobile in any of the upper floors of the building, the automobile is run off of the carrying floor 28 and on to an elevator 34 which occupies one of the stalls in rear of the space 16, except that such stall space is open continuously through the floors of the building which may vary in number and size within the scope of the invention.

In order to movably support the carrying floor 28, which latter may be of any suitable material, though preferably of wood covered with a metal sheeting 35, the flooring 29 is provided at spaced points inwardly of the rows of posts or pillars 30 with longitudinal reinforcing members, preferably I-beams 36, such beams being disposed in pairs and spaced apart to form channels 37 with restricted throats 38 located below the top surface of the floor. The floor terminates short of the edges of the beams adjacent the throats 38 and is prevented from being mutilated by reinforcing strips 39 preferably having beveled walls 40 inclined downwardly and in a direction toward the throats and conforming to the adjacent edges of the flooring. These reinforcing strips or beading are secured to the I-beams 36 as by means of fastening screws 41 and the spaces between the same are designed to accommodate the head portions of I-beams 42 which are bolted as shown at 43 between opposite inclined side edges of the carrying floor 28. These beams 42 depend into the channels 37 and their base portions are movably supported upon anti-friction devices consisting of shafts 44 rotatably journaled in rollers 45 by interposed balls or anti-friction bearings 46, the ends of the rollers being closed except where the shaft 44 protrudes therethrough for engagement in open recesses 47 of removable bearing brackets 48 which serve to rotatably

support the same. These bearing brackets are in the form of angular members, the outwardly directed upper portions 49 of which are removably or otherwise mounted in openings 50 in the web portions of the 70 beams 36.

In practice the carrying floor is preferably made about ten feet wide and of such length as to be accommodated between the pillars coöperating to form the stalls or 75 storage spaces at either side of the aisle or passageway 32, and in order to properly support the carrying floor the anti-friction members or rollers are preferably disposed one foot apart so that the floor will be supported upon a plurality thereof at either side and may be freely moved back and forth within the passageway. At times it will be necessary to renew the anti-friction members, and for this purpose at one end of 85 each of the restricted passages or throats 38 the head portions of the I-beams 36 are provided with opposed recesses or notches 51 through which the shafts and rollers carried thereby may be inserted by means 90 of a suitable clamp or tool and shifted longitudinally through the throats 38 and dropped into any of the opposed pairs of bearing brackets 48.

It will of course be understood that the 95 carrying floor 28 may be readily moved back and forth by hand or otherwise so as to be disposed in alinement with either of the respective stalls or storing spaces. The cars may be moved on to and off of the same 100 without being marred by accidents or collisions. In order to care for the repair of any of the cars which may be stored in the garage or otherwise, one of the upper floors of the garage, preferably the top floor, is 105 provided at the rear portion of one corner with a partition 52 preferably provided with transparent walls such as glass, while the side of the space 53 forming the repair shop, leading into the passageway, is provided with oppositely sliding doors 54 and 55, one sliding inwardly of the other, while the door 54 is provided with a supplemental door opening 56 to permit access to the repair shop without operating the doors 54 110 and 55.

Having thus described my invention, what I claim as new and desire to secure by Letters Patent is:

1. The combination with a reinforced concrete flooring of a building and spaced pairs of beams extending longitudinally thereof; of bearings carried by the opposed pairs of beams, rollers removably mounted in said bearings, a carrying floor having inclined side portions communicating with spaces at opposite sides thereof, and beams depending from said floor and movably supported on the rollers, said beams being operable between the first named pairs of beams. 120 125 130

2. The combination with a reinforced concrete flooring of a building and sustaining means therefor located in spaced relation providing a passageway; of spaced longitudinal reinforcing members adjacent the sides of the passageway and having an interior space communicating with the exterior by a restricted throat, rollers removably carried by the longitudinal reinforcing members between the pairs of the latter, reinforcing strips secured to said reinforcing members inwardly of said throats to pro-

vide intermediate spaces, and a carrying floor movable along the passageway and having depending beams secured thereto for supporting the same on the rollers. 15

In testimony whereof I have signed my name to this specification in the presence of two subscribing witnesses.

JAMES A. VARIAN.
